DROP SIDE CRIB

Victor J. Bukolt, Stevens Point, Wis.

Application December 26, 1951, Serial No. 263,408

7 Claims. (Cl. 5—100)

1

This invention relates to improvements in cribs of the type having slideable drop sides and an adjustable mattress frame.

Cribs of this type are made knock-down for convenience in transportation and storage, and when set up for use, are usually rather wobbly or non-rigid so that considerable strain is placed on the connections between the several parts. It is an object of the invention to provide a crib of this character with stabilizing means so that when set up for use it will not only be more rigid but will permit of freer and non-binding sliding movement of the drop sides.

Another object of the invention is to provide detachable bracket connections between the stabilizing bars and the corner posts or end members of the crib, the brackets being not only adjustable on the stabilizing bars or side rails but adjustable on the corner posts to take care of slight manufacturing variations in the sizes of the parts and also permit of the adjustment of catch members carried by the brackets and coacting with latch rods on the drop sides.

Another object is to provide an improved foot controlled latching means for the drop side which is not only highly effective in locking the drop side in its raised and lowered positions but which is also of extremely simple and inexpensive construction.

Another object is to provide effective means for stopping the drop side when it reaches its raised position.

With the above and other objects and advantages in view, the invention resides in the novel combinations and arrangements of parts and the novel features of construction hereinafter described and claimed, and illustrated in the accompanying drawings which show the present preferred embodiment of the invention.

In the drawings:

Fig. 1 is a side view of an infant's crib embodying the invention;

Fig. 2 is a detail horizontal sectional view on an enlarged scale taken on line 2—2 of Fig. 1 looking in the direction of the arrows, parts being broken away;

Fig. 3 is a detail vertical sectional view taken substantially on the line 3—3 of Fig. 2;

Fig. 4 is a detail vertical sectional view taken on the line 4—4 of Fig. 2;

Figs. 5 and 6 are detail vertical sectional views taken on the lines 5—5 and 6—6 respectively of Fig. 4;

Fig. 7 is a detail vertical sectional view taken substantially on the line 7—7 of Fig. 1, parts being broken away;

2

Fig. 8 is a detail horizontal sectional view taken on the line 8—8 of Fig. 1;

Fig. 9 is a detail vertical sectional view taken on line 9—9 of Fig. 3;

Fig. 10 is a perspective view of an adjustable bracket connecting an end of one of the stabilizing bars or side rails to one of the corner posts or end members of the crib;

Fig. 11 is a perspective view of a substitute form of bracket;

Fig. 12 is a perspective view of one of the latch bolts;

Fig. 13 is a perspective view of the foot actuated member for retracting the latch bolts; and

Fig. 14 is a perspective view of one of the levers associated with the latch bolts.

Referring more in detail to the drawings the numeral 11 denotes the two end members or frames and 12 the two drop sides. Each of the 20 end frames has the two corner posts 13 connected by open-work or solid panel portions 14. Each of the drop sides usually consists of upper and lower horizontal bars or rails 15 and 16 connected by spaced vertical slats 17. The drop sides are 25 guided in their vertical movement on rods 18 which pass through openings near the ends of the rails 15, 16 and have their upper ends laterally off-set and secured by screws 19 to the inner faces of the corner posts. The guide rods are spaced from the corner posts or end frames at their lower ends by the usual apertured angle brackets 20 which also support coil springs 18a on the rods as shown to cushion the downward movement of the drop sides.

The rectangular spring frame which supports the mattress is indicated at 21 and it is mounted for both vertical and angular adjustment. That mounting is accomplished by providing at the four corners of the frame swinging hangers 22,

40 each having at its inner end a bent pivot portion 23 removably mounted in a bearing plate 24a riveted on an end portion and near one corner of the mattress frame 21, the latter being preferably made of angle metal. The outer ends of

45 the hangers are formed with bent or angularly projecting pivot portions 24 with ball-like or headed extremities. The outer portions 24 are engageable with any of vertical series of stirrup-like or hook-shaped lugs 25 struck out of metal plates 26 secured by screws 27 to the inner faces of the corner posts. The stirrup plates 26 are fastened to the corner posts at the same elevation and it will be apparent that when the four

50 hangers 22 have their outer ends 24 engaged with the bearing lugs 25 disposed in the same horizontal plane, the mattress frame will be supported

55

horizontally and may be raised or lowered or angled lengthwise of the crib by positioning the ends 24 in appropriate lugs 25.

For the purpose of stabilizing the crib and maintaining the guide rods perpendicular and in parallel relation to each other so that the drop sides may slide freely without binding, I connect the two ends by two side rails or bars 28. These stabilizing bars may be of wood or metal and have adjustably connected to their end portions metal brackets 29 which are detachably and adjustably connected to the corner posts 13 as presently described. The lower portions of the adjustable brackets 29 are of right angular shape having inner longitudinally disposed arms 30 and outer transversely disposed arms 31. Each bracket is formed by stamping and bending a heavy metal plate as shown in Fig. 10. To strengthen the right angular bend connecting the two arms, a portion of the metal is stamped to form a stiffening rib 32 extending into each arm. The inner horizontal arm is a generally rectangular plate adapted to abut the outer face of one of the bars 28 and is formed with longitudinally extending slots 33 to receive bolts or screws 34 to adjustably fasten it to an end portion of the bar. The outer arm 31 is also a flat plate adapted to abut a flat area on a corner post but it is extended vertically much higher than the upper edge of the arm 30, its upper portion being reduced in width and bent at right angles to provide a flat horizontal lug 35. The latter is so shaped and disposed that it serves as a brace for one of the rods 18 and also as a stop to positively limit the upward movement of a drop side at one end of the latter. As seen in Fig. 7 the lug 35 has a hole or opening 36 through which the rod 18 extends and its flat bottom is adapted to be engaged by the upper surface of an end portion of the lower rail 16 of the drop side to positively limit the upward movement of the latter. Struck upwardly from the inner portion of each of the lugs 35 is a bearing hook 25^a which serves the same purpose of one of the hooks 25, thereby increasing the range of adjustment of the mattress frame 21. The adjustable connection between the bracket arm or plate 31 and the corner post includes two headed screws 37 and 38 and two slots 39 and 43. The slot 39 is formed in the lower portion of the plate 31 and has a lower circular portion of larger diameter than the head of screw 37 which pass through the slot and is threaded in the post. The slot 39 is vertically elongated and its upper end corresponds to the diameter of the shank of the screw. The upper slot 43 is L-shaped having a horizontal portion 43^a corresponding to the diameter of the shank of screw 38 and a vertical portion which is the same shape as the lower slot 39, its lower circular portion being of a size to fit over the head of screw 38. When the screws 37, 38 are loosened, the circular lower portions of the two slots may be passed over the heads of the two screws and the bracket 29 may then be lowered so that the shanks of the screws may be disposed in the small upper portions of the slots. When the parts are in that position the upper or arcuate portion 43^a permits the bracket to have a slight pivotal movement about the axis of the shank of the screw 37 for a purpose hereinafter described.

For the purpose of locking or latching either or both of the sides in their raised and lowered positions, I provide a very simple and inexpensive foot or leg controlled latching means. As shown

the latter extends along the bottom rails 16 of each of the drop sides and includes two slideable latch rods or bolts 40 with end portions that normally extend beyond the ends of the lower rail 16 under the action of coil springs 41 and are simultaneously retracted by the swinging movement of a U-shaped foot actuated member 42 disposed adjacent the central and under portion of the drop side. The latch rod 40 at each end of the drop side is slideable in a groove formed along the inner or rear lower edge of the rail 16 and is retained in such groove by a short inner angle plate 44 as shown in Figs. 3 and 7 and a long outer angle plate 45 as shown in Figs. 2 and 3. The vertical arm of the plate 45 is secured by a screw 46 against the inner face of the rail 16 and its horizontal arm is formed by three spaced tongues which engage the bottom of the rail and one or more of which may be fastened by a screw 47. The inner end of each groove communicates with a chamber or recess 48 formed in the bottom of the rail 16 and in which the spring 41 is disposed. One end of the spring is anchored to a nail as seen in Fig. 4, and its other end is anchored to a shoulder 49 formed by laterally offsetting the latch rod 40. The inner end 50 of the latter is bent at right angles and pivotally engaged with an opening in one arm of a bell-crank or T-shaped lever 51 disposed in the chamber 48. Another arm of the lever 51 is pivoted on a transverse pivot pin 52 which extends across the upper portion of the chamber 48 and is insertable into a transverse bore 53 from the inner face of the rail as will be understood on reference to Fig. 6. The third arm 54 of the lever is thrust by action of the coil spring 41 against a crank arm 55 formed at one end of the U-shape foot piece or actuator 42. The latch actuator has two angular arms 56 bent to provide two longitudinally aligned pivot portions 57 from the outer extremities of which project the crank arms 55 for simultaneously actuating the levers 51 and thereby simultaneously retracting the latch rods 40 at the opposite ends of the drop side. The pivot portions 57 are disposed along the inner face of the rail 16 and each is mounted in a bearing 58 on a plate 59 secured by screws 60. This plate as shown in Fig. 6 retains the pivot pin 52 in its bore 53. The two crank arms 55 of the U-shaped actuator swing in transverse slots 61 formed in the inner face of the rail 16 and in communication with the chamber 48. It will be seen that when the foot piece or actuator is pushed inwardly and rearwardly, the projecting ends of the two latch rods 40 will be simultaneously retracted. The free ends of the latch rods coat with keepers or catch lugs 62 formed on the brackets 29 to lock or retain the drop side in its raised or closed position, and also with keepers or catch lugs 63 formed on the angle brackets 20 to lock or retain the drop side in its open or lowered position. The keeper 63 is in the form of a downwardly inclined tongue or finger struck from the angle plate 20 along its inner edge, and its lower end is formed with a curved seat 64 under which an end of one of the rods 40 extends to prevent upward movement of the drop side. The keeper or catch is disposed in the path of vertical movement of the latch rod and the downward inclination of the keeper causes the projecting end of the latch rod to be retracted as the drop side slides downwardly. When the cushioning spring 18^a is compressed by the downward movement of the drop slide,

the end of the latch rod is spring projected to engage the seat 64. The keeper or catch 62 is similar but is inclined upwardly so that the end of the latch rod will be retracted by the inclined or angular side of the keeper as the drop side is moved upwardly. The curved seat 65 at the upper end of the keeper 62 is so disposed that the latch end will engage it just prior to the engagement of the rail 16 with the stop lugs 35. By providing the slot 43 with its laterally extending portion 43^a and pivoting the bracket 29 about the screw 37, the keeper 62 may be adjusted laterally to permit it to be alined with the path of vertical movement of the latch rod 40. After adjustment the screws 38 and 37 are tightened to retain the bracket in correct position on the end post. The provision of the slots 33 in the arms 30 of the brackets 29 permit of the effective lengths of the stabilizing bars 28 to be varied. These adjustments take care of slight variations in the sizes of the parts and permit of the assembly of the parts so that the crib will not only be rigid or non-wobbly but the drop sides will have free and easy sliding movement on the guide rods 18.

The mattress frame 21 may be supported in other ways than as above described and the end frames 11 may be connected and spaced apart by other means than the side rails 28. When these rails or side bars are not used, I may substitute for the brackets 29, brackets 29^a of the construction shown in Fig. 11. Each bracket 29^a is of right angular shape having a vertical portion 31^a corresponding to the arm 31 and formed with openings 39^a and 43^b to respectively receive the screws 37 and 38. An upwardly inclined keeper or catch member 62^a is struck out of the vertical portion or plate and corresponds to the keeper 62. The horizontal arm 35^a of the bracket 29^a corresponds to the stop lug 35 and is formed with an opening through which the rod 18 extends and also with a struck out hook 25^b which serves the purpose of the hook 25^a in Fig. 9.

From the foregoing, taken in connection with the accompanying drawing, it will be seen that novel and advantageous provision has been made for carrying out the objects of the invention, and while preferences have been disclosed, attention is invited to the possibility of making variations within the scope of the invention as claimed.

I claim:

1. In a crib having end members with corner posts carrying upright guide rods spaced at their upper and lower ends from the posts, a drop side with upper and lower rails apertured to receive the guide rods and spring-projected manually-retractable latch rods slidable on the lower rail of the drop side; angle brackets each having a vertically disposed attaching plate and a horizontal stop arm apertured to receive one of the guide rods, said attaching plates being secured to the inner faces of the opposed posts with said stop arms at their tops and disposed in the path of movement of the end portions of the lower rail of the drop side to limit the upward movement of the latter, and upwardly and inwardly inclined keeper lugs on the attaching plates to coact with the latch rods to fasten the drop side in its raised position.

2. In a crib having end members with corner posts and a drop side between opposed corner posts, the drop side having upper and lower rails with vertical apertures adjacent their ends, guide rods extending through said apertures and hav-

ing off-set upper ends secured to the inner faces of the corner posts, angle brackets secured to the lower portions of the corner posts and having apertures to receive said rods to space them from the posts, an inwardly and downwardly extending latch keeper on each of said angle brackets, said keepers having seats at their lower ends, and manually-retracted spring-projected slidable latch bolts carried by the lower rail of said drop side and engageable with the seats of said keepers to fasten the drop side in its lowered position.

3. In a crib having end members with corner posts each carrying an upright guide rod with means at its ends for spacing it inwardly from a post, drop sides with upper and lower rails apertured to receive the guide rods, and manually-retractable latch bolts spring-projected beyond the ends of the lower rails of the drop sides; a right angled bracket at each corner of the crib, each bracket having a longitudinally extending horizontal arm and an outwardly extending vertical arm for disposition against one of the corner posts, two longitudinal side bars 25 each connecting the two horizontal bracket arms on the same side of the crib, a flat horizontally disposed stop lug projecting inwardly from the upper end of each of the vertical arms of said brackets, the under sides of said stop lugs being engageable by the upper sides of the end portions of the lower rails of the drop sides to limit the upward movement of the latter, said stop lugs having openings to receive the guide rods to brace them intermediate their ends, keeper lugs 35 on the intermediate portions of the vertical arms of the brackets, said keeper lugs being inclined upwardly and inwardly and having seats at their upper ends to be engaged by the projected latch bolts to lock the drop sides in their raised positions, and upper and lower headed screws in each of the corner posts to adjustably fasten said vertical bracket arms, each of the latter having lower and upper slots for said screws, the slots having enlarged lower portions to fit over the heads of the screws and reduced upper portions to receive the shanks of the screws, the reduced portions of the upper slots having lateral extensions to permit the upper portions of the vertical bracket arms to swing on arcs concentric with the shanks of the lower screws to laterally adjust the keeper lugs with respect to the path of vertical movement of the latch bolts when the drop sides are moved vertically.

55 4. The structure of claim 3 in which said longitudinally extending arms of the brackets are formed with longitudinal slots to receive screw threaded fastenings for longitudinally adjusting said brackets on said side bars.

60 5. In a crib, spaced end members supporting latch keepers, a vertically movable drop side between the end members and having a bottom rail, longitudinally slidable latch rods on each end portion of said bottom rails, said latch rods being spring projected beyond the ends of said rail for coaction with the keepers, levers for retracting said latch rods pivotally mounted on said rail at points spaced inwardly from its ends, and a U-shaped foot actuated lever extending longitudinally of the central portion of said rail and having arms pivotally mounted on said rail with crank portions for coaction with said latch retracting levers.

65 6. In a crib, spaced end members supporting latch keepers, a vertically movable drop side be-

tween the end members and having a lower horizontal rail formed in its bottom with chambers spaced inwardly from its ends and also with longitudinal grooves along its inner bottom edge, the grooves extending from the ends of the rail and opening into said chambers, said rail also having in its inner face vertically extending slots which open into said chambers, a three armed lever in each of said chambers, each lever having an upper arm mounted on a transverse pivot, a downwardly extending arm and a longitudinally extending arm disposed opposite one of said slots, a latch rod in each of said grooves and slidably retained therein by angle plates, the outer ends of the latch rods being spring projected beyond the ends of the lower rail for coaction with the keepers, the inner ends of the latch rods being disposed in said chambers and having bent ends pivotally engaged with the lower arms of said levers, and a U-shaped foot lever for simultaneously retracting said latch rods, said foot lever having arms with axially aligned bearing portions pivotally mounted on the inner face of said lower rail and with crank arms extending through said slots for coaction with the longitudinally extending arms of said three-armed levers.

7. In a crib having end members with corner posts provided on their inner faces with flat areas, upright guide rods spaced inwardly from said posts and having their upper ends rigidly secured to the latter, drop sides with upper and lower rails apertured to receive the guide rods, and manually retractable latch bolts spring-projected beyond the ends of the lower rails of the drop sides; means for stabilizing the crib and maintaining the guide rods vertical and in parallel relation comprising two stabilizing side bars extending longitudinally between the end members and offset inwardly from the associated corner posts, a right angled bracket at each corner of the crib

between said side bars and the end members, each bracket having an inner longitudinally extending horizontal arm in contact with an end portion of one of said side bars and an outwardly extending upright arm with a flat face in contact with one of said flat areas of the corner posts, said horizontal arms having longitudinal slots, said upright arms having vertically extending upper and lower slots with enlarged lower ends, the upper slots being formed with lateral extensions, a keeper lug on each of said upright arms positioned between said upper and lower slots to coact with the ends of said latch bolts, a horizontally disposed lug projecting inwardly from the upper end of each of said upright arms and formed with an opening to receive one of said guide rods, vertically spaced headed screws on each of said flat areas of the corner posts to enter the enlarged ends of the slots in one of the upright arms for detachable mounting of the brackets on the corner posts, the brackets being downwardly movable on the shanks of the screws and being capable of angular adjustment about the shanks of the lower screws by the disposition of the shanks of the upper screws in the lateral extensions of the upper slots, and screw threaded fastenings in the side bars engaged with the slots of said horizontal arms to adjustably fasten them to the end portions of said side bars.

30 VICTOR J. BUKOLT.
